UNITED STATES PATENT OFFICE

2,565,831

GAS BURNER PLATE FOR ATTACHMENT TO
COMBUSTION CHAMBER WALLS

Percy White, Birstall, England, assignor to T. & T. Vicars Limited, Earlestown, Newton-le-Willows, England, a British company

Application December 27, 1945, Serial No. 637,391
In Great Britain September 25, 1944Section 1, Public Law 690, August 8, 1946
Patent expires September 25, 1964

1 Claim. (Cl. 158—7)

1

The present invention relates to improved control means for the gas supply for gas burners.

Whilst the improvements of the present invention are generally applicable to gas burner installations operating on a mixture of air and a combustible gas, the improvements are particularly applicable to burners for the heating of ovens such as biscuit baking ovens, enamelling ovens and the like installations.

Where an oven or other chamber is heated by a number of gas burners, it often happens that one may become extinguished, or again it may be put out of action in order to cut down the total heating in the oven or to inspect or change a burner, and under such conditions it may occur that products of combustion pass back along the air or gas feed pipes and cause a choking or corrosion of gas or air filters in the pipe lines, or, in the case of an air supply at a pressure above the pressure in the oven, air may be fed to the oven when that burner is out of action, which results it is desirable to avoid.

According to the present invention separate valves are provided at the outlet ends of gas and air supply pipes, the valves being controlled by a common operating means.

Such an arrangement will allow for the closing off of the gas and air supply pipes respectively by the operation of a single control element and will further allow the shutting off of these pipes in such cases where it is desirable to detach a burner nozzle for inspection or replacement.

The invention will be further described with reference to the accompanying drawings, in which:

Fig. 1 is a front elevation of a gas supply arrangement constructed in accordance with the invention.

Fig. 2 is a plan view of part of the arrangement of Fig. 1;

Fig. 3 is a section on the line 2—2 of Fig. 1;

Fig. 4 is a section on the line 4—4 of Fig. 1.

Figs. 3 and 4 are drawn on a somewhat smaller scale than Figs. 1 and 2.

A front plate or casting 11 is adapted to be secured to the outer wall 12 of a double walled oven by bolts 13 and a sealing flange lid.

A cylindrical spacing element 14 extends between the outer oven wall 12 and an inner wall 15 and carries joint rings 16 and 17 for connection with said walls.

A burner tube 18 has a reduced external diameter end portion 18a adapted to locate in a bore in plate 11. A series of radial bores (not

shown) provide burner orifices on the portion of tube 18 which lies within the oven on the inner side of wall 15.

A Venturi element 19 fits within tube 18 near the front end thereof and presents a reduced external diameter surface on a portion 19a. A mixing tube 20 is located in the region of its front end on the portion 19a. This mixing tube has a series of radial bores 58 and is adapted to be adjusted in axial and/or angular position relative to tube 18 to select desired conditions of mixing by varying the path to be traversed from a bore 59 in tube 20 to a bore 51 in tube 18.

A high tension ignition device is constituted by ceramic or other insulating bushes 21 and 22 supported from the outer wall 12 and a radial flange on tube 18 respectively, together with a conductor 23. The inner end portion 23a of conductor 23 forms an electrode from which a spark 20 may pass to a grounded part of the equipment such as the outer surface of tube 18.

A screw threaded plug 24 is screwed in a tapped bore in the plate 11 and is itself provided with an axial tapped bore 24a and a radial bore 24b communicating therewith.

A nozzle 25 has a screw threaded shank engageable in bore 24a. The plug 24 is readily removable for inspection or replacement of nozzle 25. A coil spring 26 extends between the end of plug 24 and the Venturi element 19 to which it is attached and urges the element towards the interior of the oven against an abutment peg 27 projecting radially inwards from the tube 18. This peg acts as a key in a slot 19b in the Venturi element to lock said element against angular displacement.

The gas control valve comprises a body 28 axially bored at 28a and counterbored at 28b. A spring loaded plunger 29, having a stem axially displaceable in a bore in a plug 30 screwed into the end of counterbore 28b, urges a ball 31 disposed within counterbore 28b towards the bore 28a. A valve rod 32 having a portion 32a of fluted or cruciform section is axially displaceable in bore 28a.

Rod 32 passes outwardly of the body 28 through a packing 33 compressed by a gland plug 34 and is urged outwardly by the action of spring loaded plunger 29 by way of ball 31.

A radial bore 28c in the valve body communicates with one end of a bore or passageway 11a in the plate 11 by way of a peripheral groove. The other end of bore 11a is aligned or otherwise finds communication with radial bore 24b in plug 24.

The body 28 has a tapped side connection 28d into which is engaged the threaded end portion of a gas supply pipe 35.

The air control valve comprises a body 36 axially bored at 36a, counterbored at 36b and provided with a reduced diameter screw threaded end portion 36c. Body 36 is supported from the outer walls 12 of the oven by threaded engagement of a tapped plate piece 37 and portion 36c which passes through a hole in said wall.

A bore 11b in plate 11 is aligned with the termination of bore 36a and has its outer end closed by a screw threaded plug 38.

A valve element 39 has a reduced square solid shank portion 39a slideable within an axially extending square hole in plug 38, is bored axially at 39b, radially at 39c, and has an enlarged diameter end portion 39d. For the greater part of its length element 39 presents an external cylindrical surface slideable in bore 36a of the body, whilst the enlarged portion 39d is slideable in the counterbore 36b. Adjustment of the maximum amount of air flow is then derived by rotation of plug 38 relative to plate 11, thereby effecting variation of the extent of alignment of bores 39c and 11c.

A spring 40 acts in compression between the inner end of element 39, within counterbore 36b, and the end of a screw threaded plug 41 threadedly engaged in the end of said counterbore, urging element 39 outwardly of the oven. A tapped side connection 36d on the body 36 is engaged by a threaded end portion of an air supply pipe 42. A bore or passageway 11c in plate 11 provides communication between bore 11b and the interior end portion of mixing tube 18 which has a radial bore 18b in alignment with the adjacent termination of bore 11c.

A pair of lugs 43 project outwardly from plate 11. A control handle 44 having a finger piece 44a and a cam portion 44b is supported on a pin 45 extending through aligned bores 43a in the lugs and through a bore in the cam portion of the handle.

A bridge 46 has a reduced width portion 46a passing between the two lugs 43 and presents a cam engaging surfaces for coaction with the cam portion of handle 44. Conical depressions

46b and 46c engage hemispherical end portions of the air valve element 39 and the gas valve rod 32 respectively.

By moving the handle 44 which forms a common operating means for both the gas and the air valves through about 180° from the position shown, both the valves, open in the position shown, become closed. It will be seen that one end, namely that having the depression 46b of the bridge 46 moves through a greater distance than the opposite end of the bridge, since the gas valve rod 32 merely moves outwardly a sufficient distance to seal ball 31 in the end of bore 28a whereas the air valve element 39 moves outwardly a distance at least equal to the diameter of radial bore 39c.

I declare that what I claim is:

A gas burner for attachment to the wall of a combustion chamber having separate air and gas conduits disposed adjacent to said chamber, the combination of a plate and means for removably attaching it on said wall, said plate having separate air and gas inlet passages therein independent of but in registry respectively with the outlet ends of said air and gas conduits, said plate having a bore communicating with said air passage, a gas nozzle on said plate at the outlet end of the gas passage therein and disposed within said bore, a flange on said plate, means to maintain the said flange in sealing contact with the said wall, a normally closed spring-operated valve in said gas conduit and a valve rod carried by the plate for holding the valve open when the plate has its flange in sealing contact with said wall.

PERCY WHITE.
